STOCK REEL SPEED CONTROL MECHANISM

John H. Friedman, Tiffin, Ohio, assignor to The National Machinery Company, Tiffin, Ohio, a corporation of Ohio

Application May 24, 1950, Serial No. 163,851

4 Claims. (Cl. 242—54)

1

This invention relates to a reel for supporting coiled wire stock and more particularly to a stock supporting reel including power means arranged to uncoil the stock and advance the stock toward a machine using the same at a rate corresponding to the requirements of the machine.

In connection with the manufacture of nails, rivets, bolts and the like, it is the usual practice to support the wire stock on a reel which is freely rotatable and to unwind the stock from the reel by the pull of the feed mechanism of the machine using the wire stock. Recent improvements in machines of this type have resulted in machines that operate at a high speed compared to the prior art and this in turn results in a high rate of unwinding of the coiled stock. Another improvement in this art relates to the use of much larger and heavier coils of wire stock so as to reduce the frequency of shutting down the machine for starting a new coil of stock. The increase in the speed of unwinding and the use of larger coils has introduced certain disadvantages particularly where the speed and rate of feed of the machine using the stock is subject to variations. It will be appreciated that when a machine, such as a nail machine, is operating at a rate of 1200 nails per minute and is unwinding from a heavy coil of wire stock the rotating stock coil has considerable inertia and when the speed and rate of feed of the machine using the stock is reduced the stock coil tends to continue to turn and unwind the stock with the result that the excess unwound stock may cause tangling of the stock. A further disadvantage has developed in connection with the larger coils in that it is necessary for the feed mechanism on the machine using the stock to overcome the inertia of the heavy stock coil and this imposes an excessively high load on the feed mechanism when the machine is started from a rest position. Thus, with the prior art arrangements the ability of the feed mechanism has limited the size of coil that might be used.

It is among the objects of the present invention to provide a stock reel support and a feeding mechanism for the coiled stock support on the reel so that the coiled stock is unwound and fed to the machine using the same at a rate determined by the machine requirements.

It is a further object of my invention to provide a stock reel with a power unit and a variable speed control device between the power unit and the reel so constructed and arranged that the speed of uncoiling is automatically varied in response to the changes in the require-

2

ments of the machine using the stock so that a stock coil weighing several tons may be used and the machine operated continuously for several hours with a single supply of wire.

It is a further object of my invention to provide a stock reel and stock feeding mechanism wherein the stock coming off the reel is guided through a pivoted arm so arranged with respect to the machine using the stock that the position of the arm is varied by variations in the demand for stock in the machine using the uncoiled stock and wherein the changes in the position of the pivoted arm change the rotational speed of the stock reel.

It is a further object of my invention to provide a stock handling apparatus according to the preceding objects wherein the unwinding of the stock and feeding the same to a machine is carried out in a manner compensating for the differences in diameter between the outer convolution of the stock in a coil and the innermost convolution of said coil.

Further objects and advantages relating to economies in manufacture and efficiency in operation will appear from the following description and appended drawings wherein:

Fig. 1 is a plan view of a stock reel and feeding mechanism constructed according to my invention; and

Fig. 2 is an elevation with parts in section of the stock reel and stock feeding apparatus.

Referring to the drawings, a base 1 is provided with an upright pedestal 2 for rotatably supporting the vertical shaft 3 which carries in its upper end a stock reel support 4 having a lower flange 5 and an upright tubular section 6. The support 4 is proportioned to receive a removable spool 7 which carries a number of coils of wire stock such as the coils 8 and 9. It will be understood that the outer turn of the coil 9 may be welded to the last turn on the coil 8 so that a plurality of lengths of stock may be thus connected and used for several hours without interrupting the operation of the machine.

Machines employed for making the bolts, rivets, nails and the like usually include a stock feed mechanism mounted on the bed frame and operated in timed relation to the header slide movements so as to advance the proper length of stock into the machine for each cycle of the machine's operation. Such conventional stock feeding mechanism is indicated at 10 and includes stock feed rolls, as at 11, which are intermittently rotated by the driving mechanism 12 so as to advance a length of stock for each cycle

of the operation of the machine. The stock being unwound and advanced by the feed mechanism 10 is indicated at 13 and such stock is guided as it is being unwound through the fork 14 carried by the pivoted arm 15 and, as will be understood as this description proceeds, the position of the arm 15 determines the rate at which the stock will be unwound from the stock reels 8 and 9.

A vertically-extending supporting plate 16 is secured on the base 1 beneath the reel support table 4 and at one side of the plate 16 is supported a motor 17 and at the other side of the plate is supported a speed change mechanism indicated as at 18. The rotation of the motor is transmitted by belt 19 to the input shaft 20 of the speed change mechanism. The output shaft 21 at the top of the speed change mechanism includes a pulley and drive through belt 22 to a driven pulley carried by the reel support 4. The speed change device 18 includes an operating arm 23 and is so constructed and arranged that movement of the arm in a counterclockwise direction increases the speed of rotation of the output member 21 and movement of the controlling arm 23 in a clockwise direction decreases the speed of rotation of the output member 21. A bracket 24 is secured to the supporting plate 16 alongside of the speed change mechanism and said bracket 24 pivotally mounts the arm 15 as at 25. A pair of adjusting screws 26 and 27 are arranged adjacent the inner end of the pivoted arm 15 so as to limit the range of pivotal movement of the arm 15. The motion of the arm 15 is transmitted to the controlling arm 23 by an adjustable link 28 connected at one end to the arm 15 and at the other end to the arm 23.

It will be noted that the angle at which the stock being unwound from the reel is disposed with respect to the feed mechanism 10 and the yoke 14 of the arm 15 is such that an increase in the tension of the unwound stock between the reel 8 and the feed mechanism tends to swing the arm 15 in a counterclockwise direction, whereas a decrease in the tension in this section of unwound stock permits the arm 15 to swing downwardly in a clockwise direction to a position as indicated in the dotted lines of Fig. 2. Thus, it will be understood that an increase in the speed of the feed mechanism 10, as would occur when the machine using the stock was being accelerated, will put an additional pull on the stock being unwound from the reel and thus swing the arm 15 in a counter-clockwise direction to increase the output speed and hence the speed of reel rotation. Conversely when the feed mechanism 10 is decelerated or brought to a stop, the arm 15 will move in a clockwise direction and thus decrease and/or eventually stop the rotation of the output member 21. Although the speed change mechanism 18 illustrated is of the self-contained hydraulic type, it will be understood that other types of speed change devices may be employed such as, for instance, variable pitch V pulley and belt arrangements. It will also be appreciated that the movement of the arm 15 may be utilized to operate an excitation controller for a variable speed electric motor.

Although I have shown and described one form of my invention in considerable detail, it will be appreciated that numerous changes can be made therein without departing from the scope of the invention as defined in the following claims.

What I claim is:

1. In a coiled wire stock feeding apparatus a base having a vertically disposed pedestal, a wire

stock support mounted on said pedestal for rotation about a vertical axis, a coil of wire stock on said support arranged to be unwound by the rotation thereof, a power unit mounted on said base, a speed change device mounted on said base, said speed change device having a constant rotational speed input shaft connected to said power unit, an output shaft operatively connected to said support and a speed control lever movable from an off position which stops the rotation of the output shaft to variable on positions determining the rotational speed of the output shaft, a guide lever pivoted on said base at one end thereof on a horizontal axis, said guide lever extending laterally and upwardly from said horizontal axis whereby said guide lever turns downwardly about said axis in response to gravity, means connecting said guide lever and said control lever to move said control lever to stop position as said guide lever turns to its lowered position and a wire guide at the other end of said lever engaging the wire after being unwound from said coil, the tension in said wire effecting an upwardly turning movement of said guide lever and thereby increasing the speed of said output shaft.

2. A coiled wire stock feed apparatus responsive to demand of a wire feed mechanism comprising a vertically disposed pedestal, a rotatable support journaled in said pedestal on a vertical axis, a coil of wire stock carried by said support, a stock guide pivotally mounted adjacent said support on a horizontal axis, said stock guide extending from its mounting on said support to engage the wire stock after being unwound from the stock coil, said guide being disposed at one side of its pivotal support and being moved in response to gravity and to changes in demand by said feed mechanism effecting changes in the tension in that length of wire stock between the coil and said feed mechanism, a power unit operatively connected to said support to rotate the same and means operatively connecting said guide and said power unit whereby movement of said guide in response to increased tension resulting from an increase in demand by said feed mechanism increases the rotational speed of said support and movement of said guide in the absence of such demand by said feed mechanism stops the rotation of said support.

3. In a coiled wire stock feeding apparatus a base having a pedestal, a wire stock support mounted on said pedestal for rotation relative thereto, a coil of wire stock on said support arranged to be unwound by the rotation thereof, a power unit mounted on said base, a speed change device mounted on said base, said speed change device having a constant rotational speed input shaft connected to said power unit, an output shaft operatively connected to said support and a speed control means movable from an off position which stops rotation of the output shaft to variable on positions determining the rotational speed of the output shaft, said speed control means including a guide lever pivoted on said base biased in one direction formed with a wire guide engaging the wire after being unwound from said coil, the tension in said wire effecting turning movement of said guide lever in the other direction and thereby increasing the speed of said output shaft.

4. In a coiled wire stock feeding apparatus a base having a pedestal, a wire stock support mounted on said pedestal for rotation relative thereto, a coil of wire stock on said support arranged to be unwound by the rotation thereof, a

power unit mounted on said base, a speed change device mounted on said base, said speed change device having a constant rotational speed input shaft connected to said power unit, an output shaft operatively connected to said support and a speed control means movable from an off position which stops rotation of the output shaft to variable positions determining the rotational speed of the output shaft, said speed control means including a control member biased in one direction formed with a wire guide engaging the wire after being unwound from said coil, the tension in said wire effecting movement of said control member in the other direction and thereby increasing the speed of said output shaft. 15
